JAN 30, 1883

UNITED STATES PATENT OFFICE.

GEORGE F. EBERHARD, OF CLEVELAND, OHIO.

DESIGN FOR A HARNESS-BIT.

SPECIFICATION forming part of Design No. 13,548, dated January 30, 1883.

Application filed November 11, 1882. Term of patent 14 years.

To all whom it may concern:

Be it known that I, GEORGE F. EBERHARD, of Cleveland, in the county of Cuyahoga and State of Ohio, have invented and produced a new 5 and original Design for Harness-Bits, of which the following is a specification, reference being had to the accompanying photographs, making a part thereof.

My invention relates to a novel design for 10 harness-bits; and it consists in certain features of configuration and ornamentation, which will be more fully described hereinafter, and particularly pointed out in the claims.

In the accompanying photographs, Figure 15 1 represents what is known in the market as a "half-cheek" snaffle-bit, and Fig. 2 what is known as a "full-cheek" snaffle-bit. Both of these bits embody my design, which relates to the form and ornamentation of the cheek-piece.

20 In both figures the same part will be found designated by the same letter of reference.

A is the bit proper, B B are the loops or rings to which the reins are attached, and C C are the cheek-pieces. The cheek-pieces are 25 frame-like, their sides spreading as they leave the neck portions, then continuing in straight and parallel lines, and finally rounding at the outer extremities. These frame-like cheek-pieces are made more fanciful by connecting

the inner edges of their side bars by ornaments—such as *n*—each of which is composed of two parallel bars set inclinedly to the side bars of the frame, and three parallel bars joining the two inclined bars just referred to, and running parallel with the side bars of the 35 frame.

I do not limit my invention to either a half-cheek bit or a full-cheek bit, or to a snaffle-bit, or to other known kinds of bit, because my novel design may be employed in any of these 40 bits; but

What I claim as my invention, and desire to secure by Design Letters Patent, is—

1. A harness-bit the cheek-pieces of which have a configuration substantially such as 45 shown and described.

2. A cheek-piece for a harness-bit made frame-like, with straight sides and rounded end, as shown and described.

3. A cheek-piece for a harness-bit made 50 frame-like and ornamented with inclined and perpendicular bars *n*, as shown and described.

In testimony whereof I have hereunto set my hand this 3d day of November, 1882.

GEORGE F. EBERHARD.

In presence of—

ALFRED A. POPE,
WALTER A. BIDDLE.
